[57] CLAIM

The ornamental design for a sport top for a van conversion, as shown and described.

DESCRIPTION

FIG. 1 is a perspective view taken from the left front side and above, showing the new design of the sport top for a van conversion;

FIG. 2 is a front elevational view thereof;

FIG. 3 is a top plan view thereof;

FIG. 4 is a left side elevational view thereof;

FIG. 5 is a rear elevational thereof; and

FIG. 6 is a perspective view thereof taken from the right front side and above on a reduced scale, it being understood that the broken lines are for illustrative purposes only.

FIG. 3.

FIG. 4.

FIG. 5.

FIG. 6.
